UNITED STATES PATENT OFFICE.

LEO S. TREESE, OF DETROIT, MICHIGAN.

DESIGN FOR AN AUTO-LAMP.

57,286.

Specification for Design.

Patented Mar. 8, 1921.

Application filed July 11, 1918. Serial No. 244,507. Term of patent 14 years.

To all whom it may concern:

Be it known that I, LEO S. TREESE, a citizen of the United States, residing at Detroit, in the county of Wayne and State of Michigan, have invented a new, original, and ornamental Design for Auto-Lamps, of which the following is a specification, reference being had to the accompanying drawings, forming a part thereof, wherein—

Figure 1 is a side elevation of the invention.

Fig. 2 is a front elevation.

I claim:

The ornamental design for an auto lamp substantially as shown.

LEO S. TREESE.
